UNITED STATES PATENT OFFICE.

MATTHEW C. JACKSON, OF BUCKNER, ARKANSAS.

WASHBENCH.

1,121,506.

Specification of Letters Patent.

Patented Dec. 15, 1914.

Application filed March 3, 1914. Serial No. 822,214.

To all whom it may concern:

Be it known that I, MATTHEW C. JACKSON, a citizen of the United States, residing at Buckner, in the county of Lafayette and 5 State of Arkansas, have invented a new and useful Washbench, of which the following is a specification.

This invention relates to wash benches of that type particularly designed for holding 10 washing machines of the "roller" style.

One of the objects of the invention is to provide means whereby a washing machine can be supported readily within either of two tubs mounted on the wash bench, the 15 structure on which the washing machine is supported being reversible so that said machine can be easily placed within either of the tubs.

A further object is to provide means for 20 holding the washing machine in position, said means being removable readily from the wash bench so that the entire structure is thus rendered easy to handle and can be stored in a small space.

25 A further object is to provide means whereby the washing machine can be supported rigidly within metal tubs, there being means provided for preventing the tub from spreading apart under the weight to 30 which it is subjected while the washing machine is in use.

A further object is to provide tub engaging members mounted in a peculiar manner, whereby they can be supported out of the 35 way when not in use.

With the foregoing and other objects in view which will appear as the description proceeds, the invention resides in the combination and arrangement of parts and in 40 the details of construction hereinafter described and claimed, it being understood that changes in the precise embodiment of the invention herein disclosed, can be made within the scope of what is claimed, without 45 departing from the spirit of the invention.

In the accompanying drawings the preferred form of the invention has been shown.

In said drawings:—Figure 1 is a vertical 50 longitudinal section through the wash bench and showing two tubs thereon and the support for the washing machine extended into one of the tubs, the position of said support when extended into the other tub, being indicated by dotted lines. Fig. 2 is an en-

larged section on line A—B Fig. 1, the wash bench being removed. Fig. 3 is an enlarged side elevation of the supporting frame for holding a washing machine.

Referring to the figures by characters of reference 1 designates the top of the bench, the same being supported at its ends by legs 2 suitably connected thereto and said top being made up preferably of two members 3 connected at their sides by straps 4, these straps also serving to hold the members 3 spaced apart. An upstanding frame 5 is insertible between the members 3 and includes side members 6 connected by cross rods 7 and 8, there being legs 9 at the lower ends 65 of the frame for holding said frame in an upright position. The ends of the rod 8 extend laterally beyond the sides of the frame and are adapted to project under and to be engaged by the straps 4.

The ends of the rod 7 project laterally beyond the sides of the frame and are adapted to engage that portion of the structure designed to support a washing machine. This last named supporting structure consists of 75 side strips 9 connected at one end by a cross strip 10 on which is arranged a cleat 11 adapted to be engaged by a washing machine, not shown, said machine being one of that type known as a "roller" washer. 80 A slot 12 is arranged longitudinally within 85 an intermediate portion of each strip 9 and each slot is open at a point between its ends, as shown at 13, this opening extending to the lower edge of the strip 9. As shown 90 particularly in Fig. 2, the cross strip 10 is extended under the ends of the side strips 9 while the cleat 11 is extended up to and between said side strips. Centering plates 14 are mounted upon the bottom face of the 95 cross strip 10 at the ends thereof, each of these plates being provided with a longitudinal slot 15 for the reception of a clamping screw 16.

Extending between the ends of the cross 100 strip 10 and of the side strips 9 are fingers 17 having upstanding terminals 18 projecting into the side strips 9. The outer ends of these fingers are hooked as shown at 19, the terminals of the hooks abutting against the 105 outer faces of the side strips 9. These hooks are arranged in pairs, as shown in Fig. 3, and the hooks of each pair engage eyes 20 formed at the ends of bails 21 which, as shown particularly in Fig. 2, are bent to 110

form terminal hooks 22. The eyes 20 are elongated for the purpose hereinafter set forth.

The free ends of the side strips 9 are recessed, as shown at 23 and extending laterally from the sides 6 are holding lugs 24 adapted, when the strips 9 are swung to vertical positions and with their recessed ends 23 lowermost, to engage said recessed ends 10 when the strips 9 are slid downwardly. Thus the said strips 9 will be held vertical and with the cross strip 10 removed from above the members 3 of the bench.

The members 3 are adapted to support 15 ordinary metal wash tubs, such as indicated at 25 and by placing the openings 13 above the terminals of cross rod 7, the said terminals can be caused to enter slots 12 and become seated in the upper ends of the slots.

20 Arms 9 can be swung downwardly until the hooked portions 22 of the bails 21 are brought into engagement with the upper edge of the tub, thus supporting cross strip 10 within the tub. The plates 14 can be 25 adjusted longitudinally so as to engage the inner surface of the wall of the tub and by tightening the screws 16, these plates can be held in the positions to which they are adjusted. A washer of the usual "roller" 30 type can be mounted on the strip 10 and used as ordinarily. By slipping the side strips 9 upwardly along the terminals of rod 7 and then lifting the strips off of the terminals, the entire washer supporting 35 structure can be reversed to the position indicated by dotted lines in Fig. 1, thus supporting the washer within the other tub 25. It will be seen that the plates 14 prevent lateral shifting of the structure relative to 40 the tub and by providing these plates together with the hooked bails 21, the tub will be prevented from spreading apart under the weight to which it is subjected while in use.

45 When the apparatus is not in use, the vertical frame 5 can be removed, the side strips 9 can be detached from the terminals of the cross rod 7, and the hooked bails 21 can be slid downwardly relative to the eyes 19 so 50 that the said bails will thus be supported close to and substantially parallel with the

side strips 9, as shown by dotted lines in Fig. 2. Thus the entire structure can be compactly arranged for storage.

Importance is attached to the fact that 55 the structure made up of the side strips 9 and cross strip 10 can be quickly detached and reversed so as to support a washing machine in either of two tubs. This permits the operator to be seated at either side of 60 the structure for the purpose of operating the machine.

In order that the strips 9 may be properly secured upon the rod 7, a pin 26 can be inserted into each of the strips 9 so as 65 to extend across the slot 12, and thus prevent the strip from riding upwardly along the rod 7 and becoming accidentally detached therefrom. This pin 26 can be easily removed whenever it is desired to detach 70 the side strips and reverse them.

What is claimed is:—

1. The combination with an upstanding structure, and a washer supporting structure connected thereto and including a cross 75 strip, of hooked bails slidably connected to the ends of cross strip and adapted to slide upwardly and downwardly and to swing relative thereto, said bails constituting means for engaging the upper edge of the 80 wall of a tub at opposed points.

2. The combination with a supporting structure and a washer supporting structure connected thereto and including a cross strip, of hooked bails adjustable angularly relative to the end portions of the cross strip and adapted to diverge upwardly into engagement with the upper edge portion of a tub at opposed points, means coöperating with said bails and slidably engaged thereby for guiding the bails inwardly against the sides of the washer supporting structure when said bails are moved downwardly relative to said structure.

In testimony that I claim the foregoing 95 as my own, I have hereto affixed my signature in the presence of two witnesses.

MATTHEW C. JACKSON.
